UNITED STATES PATENT OFFICE.

CHARLES B. MILLS, OF BALTIMORE, MARYLAND, ASSIGNOR OF ONE-FOURTH TO
ALFRED J. CARR, OF BALTIMORE, MARYLAND.

ELECTRIC-LAMP SOCKET.

1,131,724.

Specification of Letters Patent. Patented Mar. 16, 1915.

Application filed September 24, 1913. Serial No. 791,631.

To all whom it may concern:

Be it known that I, CHARLES B. MILLS, a subject of the King of Great Britain, residing at Baltimore, State of Maryland, have 5 invented new and useful Improvements in Electric-Lamp Sockets, of which the following is a specification.

This invention relates to improvements in electric lamp sockets and has particular application to means for securing such devices to cables and placing the same in electrical contact therewith.

In carrying out the present invention, it is my purpose to provide a device of the 15 class described which will be found especially useful in temporary work—such, for instance, as the securing of electric lamps to suspended cables for decorating purposes, and whereby the lamps and 20 socket members will be rigidly and securely held to the cable so that vibration of the lamp or socket member independently of the cable is eliminated.

It is also my purpose to provide means 25 for effecting a temporary connection between the lamp socket and the cable which will be constructed in such manner that the upper surface of the socket will abut against the adjacent portion of the cable, the securing 30 devices being so formed that removal of the socket member from the cable by pulling such member in a direction at right angles to the cable is avoided. Furthermore, I aim to provide a device of the type set forth 35 which will embrace the desired features of simplicity, efficiency and durability which may be readily and conveniently applied to any type of lamp socket member or base, as such member is sometimes called, now in 40 use, and which will hold the lamp securely to and in electrical engagement with the cable.

With the above and other objects in view, the invention consists in the construction, 45 combination and arrangement of parts hereinafter set forth in and falling within the scope of the claim.

In the accompanying drawing: Figure 1 50 is a view in side elevation of a lamp socket member showing the connection between such member and the cable. Fig. 2 is a cross sectional view through the cable. Fig. 3 is a cross sectional view through one form 55 of lamp socket equipped with my present invention. Fig. 4 is a similar view through

another form of lamp socket equipped with my invention. Fig. 5 is a top plan view of the socket. Fig. 6 is a view in side elevation of the lamp socket or receptacle.

Referring now to the accompanying drawing in detail, the numeral 1 designates a lamp socket which, in Figs. 1 and 3 of the drawing, is shown to be of the Edison type, such socket comprising an outer casing 2 of insulating material and having a closed end 3 and an open end 4. Mounted within the casing 1 and suitably secured thereto is an interior-threaded metallic shell 5 designed to receive the exteriorly threaded plug formed on the end of the lamp bulb. 60

In the present instance, the upper surface of the end wall 3 of the casing 2 is formed with recesses 6, 6 and within each recess is disposed the headed end 7 of a pin 8. The headed end 7 of each pin is suitably fastened 65 to the bottom wall of the respective recess 6 and passed through the bottom wall of each recess is a headed stud 9 having one end thereof fastened to the headed end of the respective pin. The headed ends of the 70 studs 9, 9 extend into the shell 5 and one of such studs is connected with the upper end of the shell, while the remaining stud is connected to a spring contact 10 disposed within the shell 5 approximately 75 centrally thereof and insulated therefrom and arranged in the path of movement of the contact carried on the upper end of the lamp plug. The pointed extremities of the pins 8 are disposed in a plane at an angle to 80 the plane of the normal axis of the pins and, in the present instance, are bent at an acute angle to such axis so that a heel 11 is formed on each pin at the junction of the bent portion with the straight portion, such heels 85 being disposed in proximity to the upper surface of the closed end 3 of the casing 2. 90

In practice, the pointed extremities of the pins 8, 8 are forced through the insulation on the cable and into the wires or strands 100 constituting the cable and owing to the pointed extremities of the pins being disposed in a plane at an angle to the normal axis of the pins, it will be seen that it is impossible to remove the socket from the 105 cable by a pull at right angles to the plane of the cable, while the heels 11, being disposed in proximity to the upper surface of the closed end of the casing, enable the outer surface of such end to abut against the ad- 110

ja²cent portion of the cable thereby preventing vibration of the socket member and lamp independently of the cable.

In Fig. 4 of the drawing, I have shown 5 the pins as applied to a lamp socket of the Ediswann type and in this form of my invention the headed ends of the pins are disposed within the closed end of the casing 2 of the socket and have the heads thereof 10 counter-sunk in the inner surface of such end. Suitably connected to the inner surface of the closed end wall 3 and depending therefrom in axial alinement with the heads of the pins are sleeves 12, 12 in each of which 15 is mounted for sliding movement a contact stud 13, coiled expansion springs 14 being interposed between the inner ends of the contact studs 13 and the heads 7 of the pins 8, such springs acting to hold the contact 20 studs normally projected out of the sleeves so that when the plug of the lamp is inserted within the socket a good electrical contact between the pins 8, 8 and the lamp will be provided. As usual, the open end of the 25 socket is formed at diametrically opposite points with bayonet slots 15 opening onto the outer edge of the socket member and co-operating with the pins on the lamp plug to hold the latter in place.

30 From the foregoing description taken in connection with the accompanying drawing, the construction, mode of operation and manner of employing my invention will be

readily apparent. It will be seen that I have provided a lamp socket whereby an electric lamp may be readily and conveniently attached to a suspended cable for decorative purposes and whereby accidental displacement of the lamp, incident to the 40 swinging of the cable, is avoided.

In the present instance, the cable, as shown in Figs. 1 and 2 of the drawing, is of the duplex type, one of the pins entering one wire of the cable, while the remaining pin is passed into the other wire.

45 I claim:

The combination with a cable, of a lamp socket member, headed pins having the head ends thereof embedded in said socket member and electrically connected therewith, and the shanks thereof disposed at an acute angle to the normal axis of the pins and designed to penetrate the cable, the bent portions of the pins forming, at the junction with the straight portions, heels disposed in proximity to the upper surface of the socket member whereby the upper surface of such socket is caused to abut the adjacent portion of the cable and maintained in engagement with the cable.

50 55 In testimony whereof I affix my signature in presence of two witnesses.

CHARLES B. MILLS.
